COMBINATION SLIP AND BRASSIÈRE

Amanda Ysidra Heinkel, Hollywood, Calif.

Application July 26, 1948, Serial No. 40,655

1 Claim. (Cl. 2—73)

1

The present invention relates to an improved combination slip and brassière incorporating a novel adjusting arrangement allowing the brassière portion to receive and support the breasts so as to improve the bust contour of the wearer, as well as to benefit those parts of the body, by providing muscular support thereto and to hold the breasts at a more or less normal and proportionately normal contour.

An object of the present invention is to provide an improved combination brassière and slip incorporating a novel adjusting means for achieving the above mentioned desirable results.

Another object of the present invention is to provide an improved combination slip and brassière incorporating but one single strap for comfortable wear during summer months when one wants as much coolness as possible.

Another object of the present invention is to provide an improved combination slip and brassière especially adaptable for wear under sheer blouses.

Another object of the present invention is to provide an improved combination slip and brassière characterized by the fact that the back of the brassière section is loose from the slip to first hold the brassière firmly in place and second, to relieve the slip of any strain when the wearer is in motion.

Still another object of the present invention is to provide an improved combination slip and brassière in which the back section fastens like a conventional brassière and is adjustable.

Another object of the present invention is to provide an improved combination slip and brassière incorporating a novel brassière section adjusting means normally concealed within the slip portion.

The features of the present invention which are believed to be novel are set forth with particularity in the appended claim. This invention itself, both as to its organization and manner of operation, together with further objects and advantages thereof, may be best understood by reference to the following description taken in connection with the accompanying drawings in which:

Figure 1 is a perspective view of a combination slip and brassière embodying the present invention.

Figure 2 is a view looking at the back of the garment shown in Figure 1 with the brassière section fastening means in engagement.

Figure 3 is a sectional view taken substantially on the line 3—3 of Figure 2.

2

Figure 4 is a view similar to the view shown in Figure 2, but with the brassière section fastening means disengaged.

The combination brassière and slip incorporates in a single garment a brassière section 10 and a slip section 11, both sections being supported by shoulder straps 12, 13 with the two cup portions of the brassière built in and forming a portion of what would otherwise be the top front portion of the slip. The length of the shoulder straps 12, 13 may be adjusted in conventional manner by use of the conventional strap adjusting members 14.

While the present invention is applicable to combination slips and brassières in which the brassière cups may be of different construction, I prefer to use, so far as is applicable, the construction shown in my copending application, Serial No. 739,161, filed April 3, 1947, now abandoned for brassière. The slip section 11 may be of conventional construction and blends in with the construction of the brassière section, an important feature being that the slip conceals the adjusting means for the brassière section and in part supports the same in convenient position when such adjusting means is detached.

The adjusting means for the brassière section includes a pair of internal flap members 15, 16 each stitched at 17, 18, respectively, along opposite side seams of the garment and with the inner ends of such flap members 15, 16 carrying cooperating fastening means 20, 21 of the hook and eye type. The hook fastening member 21 has passing therethrough a flexible tape 24 which has its ends stitched to the end of flap member 15. The plurality of eye fastening members 21 are fastened in the cloth portion 26 which, in turn, is stitched to the other flap member 16.

It is noted that the shoulder straps 12, 13 are not only stitched to the upper edge of the back of the slip portion 11 but extend further and are stitched respectively to the flap portions 15, 16 to hold them in a convenient position when the fastening means 20, 21 is disengaged.

A narrow elastic band 30 threaded through a sleeve-like portion 31 at the sheared top of the back of the slip provides an elastic structure arranged to form fit a person either with broad shoulders or with narrow shoulders so that the back of the slip always hugs the back of the wearer to provide a form fit. The ends of the elastic band 30 may likewise be stitched at the side seams.

While the particular embodiments of the present invention have been shown and described, it

will be obvious to those skilled in the art that changes and modifications may be made without departing from this invention in its broader aspects and, therefore, the aim in the appended claim is to cover all such changes and modifications as fall within the true spirit and scope of this invention.

I claim:

A combination slip and brassière comprising a brassière section and slip section, said brassière section having a pair of side edges, said slip section having a front panel and a back panel, said brassière section and said slip section being stitched together with the front panel of the slip section secured at its top edge to the lower-most edge of said brassière section, and with the back panel of the slip section secured to the side edges of the brassière section to form a back portion for the brassière section, a pair of flap member each having one of its ends attached to 15 said brassière section at a corresponding one of said side edges and extending within and lying

adjacent the inner surface of said back portion, the other ends of said flap member carrying resiliently supported cooperating fastening means, a pair of shoulder straps, said shoulder straps each having their forwardly disposed ends stitched to said brassière section and having their rearwardly disposed ends stitched to both said back portion and also to said pair of flap members.

AMANDA YSIDRA HEINKEL.
